UNITED STATES PATENT OFFICE.

EMIL PODSZUS, OF BERLIN-FRIEDRICHSHAGEN, GERMANY.

PROCESS OF AND APPARATUS FOR OBTAINING POWDERS OF GREAT FINENESS.

Original application filed July 1, 1922, Serial No. 572,340. Divided and this application filed September 2, 1924, Serial No. 735,253, and in Germany July 12, 1921.

My invention has reference to a method at all. It is possible by acting in this manner, to convert the fine material in a very short time into large quantities of colloid. The process becomes particularly efficient by simultaneously treating only fine and coarse particles, the medium sized granules being eliminated as much as possible, inasmuch as these particles possess only in a very imperfect degree the qualities referred to of the coarse particles, and because, on the other hand, these medium sized granules interfere with the systematic comminution of the small particles, and produce a rapid wear of the coarse particles. In the practical execution of the process, the fine particles of the material to be comminuted are treated according to the process in certain proportions together with small balls of steel or the like. With a proper adjustment of the proportions of the fine particles and of the steel balls, the latter do not impinge directly upon each other, there being always a sufficiency of fine particles between them when the impact is to take place, and therefore, no appreciable or noticeable wear of the steel balls takes place, but only the fine particles are rubbed up. By this operation, large quantities of metals may be converted into colloids up to 70 or 80 percent in from four to five hours. The process may, for instance, be applied to particles of mass of a size of one hundredth of a millimeter or less, while the coarser particles, in the present instance the steel balls, possess a diameter of, say one millimeter.

In the further evolution of my process, it is possible to still further considerably increase the degree of fineness and to obtain in a comparatively short time large quantities of powder of colloidal fineness. This is due to the fact that with the process described in my said application, a certain state of equilibrium occurs after some time, in which even after prolonged grinding, any appreciable comminution can no longer be obtained. This state of equilibrium terminates in the case of coarser particles in the ratio of lightness of weight of the material in view of the fact that the mass of individual particles impinging upon each other, is gradually reduced to such an extent that any appreciable progress in the disintegrating operation becomes impossible.

In accordance with the present invention therefore, fine particles are submitted to the comminuting operation accompanied by considerably coarser particles. The coarser particles possess the necessary mass in order to produce in this case the necessary forcible impact. With a proper selection of the proportions of the ingredients of fine and coarse particles there are so many fine particles contained between two impinging coarse particles that the fine particles are pounded, rubbed up or ground between them, while the coarser particles are submitted to only a rather slight or no appreciable wear

Where the greatest degree of purity of the mass is of importance it is advisable to use coarser granules of the mass to be disintegrated itself as a treating medium for the finest powder, instead of using steel balls or other foreign bodies. According to the experiments made, it has been found to be of advantage to employ a large amount of coarse particles or of steel balls or the like. However, the proportion of these coarser ingredients, provided they should not be greatly attacked, should not exceed one half the amount of the fine powder.

The process may also be carried out in such a manner that instead of adding coarser particles, the fine powder is mixed with binding agents in suitable proportions, the said binding agents causing the formation of lumps of some size, and the said lumps being then caused to act upon each

other as coarse ingredients, and effecting the destruction and crushing of the fine particles of powder.

In the accompanying drawing an embodiment of the apparatus for carrying out my new process is diagrammatically shown; Fig. 1 being a vertical section through the apparatus, and Fig. 2 a view of details turned about 90°.

- 10 In a casing 1, two shafts 2 and 3 are rotatably journaled, which shafts carry the air propellers 4 and 5. In front of these air propellers there are provided transverse members 6 and 7, as more clearly shown in Fig. 2.
- 15 The material to be treated, as well as the coarser particles, steel balls, etc., are introduced into the casing 1, through an opening 8, which can be closed. Thereupon, the propellers 4 and 5, by means of the pulleys 9 and 10 mounted on the propeller shafts are rapidly rotated in opposite directions. By these rotations, air currents are produced which, as indicated by the arrows 11 and 12 impinge upon each other in the center of casing 1.
- 25 Through the said transverse members 6 and 7, also lateral displacements are imparted to the said air currents, so that the particles of the material to be treated, suspended in the air currents, not only impinge upon each other, but also frictionally engage each other, resulting in an abrading effect. The air propellers 4 and 5 draw away the air from the lateral portions of casing 1, forcing the air toward the center of the casing, with the result that at this place, a continuous violent impact of air currents is produced. The air currents thereby are divided, and passing around the two propellers in the direction of the arrows, as shown in Fig. 1, are again caught by the propellers, and then are again projected toward the center of the casing. Between the propellers, there will thus be formed as indicated by the arrows, continuously circulating whirling air currents, in which the particles of the material to be treated are compelled to participate.

In order that these circulating whirling air currents may be produced in a sufficient amount, it is advisable to provide in casing 1, behind the air propellers, sufficiently large cavities of a suitable shape, thereby facilitating the formation of the said air currents. The air propellers 4 and 5 are made of such a pitch, that the thrust of the air currents near the center of the casing is of substantially equal force as the thrust occurring at the outer ends of the wings of the propellers.

- 50 As the steel balls and coarse particles introduced into the casing, together with the material to be treated participate in the continuous circulating of the whirling air cur-

rents produced in the casing, they consequently meet in continuous violent impacts, whereby the material between the said steel balls and the said coarser particles is comminuted to an extraordinary degree of fineness.

The discharge of the comminuted material from the casing is conveniently effected in this way, that a current of gas or air is introduced into the casing through the conduits 17 and 18, while the closing slide 20 is opened, so that the powder is blown out of the casing, and is caught above the same. This discharging current must however, be so determined as to its strength, that the formation of the whirling air currents within the casing is not interfered with.

I claim as my invention:

1. The process of producing very fine powders of colloidal fineness, which consists in producing high-speed mutually impinging whirling gas or air currents within a closed casing, causing said currents to circulate within said casing at the rate of several thousand times or more per minute, thereby causing the particles of the material to be treated suspended in said currents to continually impinge upon each other, and at the same time adding to the particles of the material to be treated a certain amount of coarser particles of the same or other material, to thereby increase the mutual impact of the particles of the material to be treated.

2. The process as specified in claim 1, in which the said coarser particles constitute to about one-third of the amount of the material to be treated.

3. The process as specified in claim 1, in which the said coarser particles consist of fine steel balls.

4. In an apparatus for producing very fine powders of colloidal fineness, the combination with an entirely enclosed casing, of air propellers rotatably mounted within said casing and spaced so as to provide open spaces at the side and back of said propellers, means for revolving said propellers at a high rate of speed in opposite direction to produce whirling air currents in said spaces, and means, such as small steel balls, within said casing, having a larger diameter than the particles of the material to be treated, and adapted to be carried along by the said whirling air currents, so as to continually act on the particles of the material to be treated.

5. The combination as set forth in claim 4, comprising also lateral members provided in front of the said propellers for imparting to the whirling air currents a lateral movement.

In testimony whereof I affix my signature.
EMIL PODSZUS.
